UNITED STATES PATENT OFFICE.

HARVEY T. WHITE AND PERCY H. WHITE, OF BROOKLYN, NEW YORK, ASSIGNEES TO
H. TYSON WHITE'S SONS, OF NEW YORK, N. Y., A PARTNERSHIP.

DISPLAY BOX.

Application filed August 6, 1921. Serial No. 490,408.

To all whom it may concern:

Be it known that we, HARVEY T. WHITE, a citizen of the United States, residing at New York city, borough of Brooklyn, in the county of Kings and State of New York, and PERCY H. WHITE, a citizen of the United States, residing at New York city, borough of Brooklyn, in the county of Kings and State of New York, have invented certain new and useful Improvements in Display Boxes, the following being a full, clear, and exact disclosure of the one form of our invention which we at present deem preferable.

For a detailed description of the present form of our invention, reference may be had to the following specification and to the accompanying drawing forming a part thereof, wherein—

Fig. 1 is a front elevation of our completed box;

Fig. 2 is a side elevation thereof;

Fig. 3 an interior view with the front removed, and

Fig. 4 is a detail.

Our invention relates to a paper or pasteboard box for the display of bottles or other articles such, for instance, as perfumery bottles, on shop counters. It resides in a construction whereby the bottles may be supported in an elevated or arched line with their tops projecting above the front face of the box and in front of the higher back of the box. Each bottle is contained within a separate receiving cell formed by partitions on either side whereby, in the event of the removal of part of the articles, the rest will still be held in their upright positions. The construction is also one which may be manufactured at a minimum cost and is light in weight as well as attractive in appearance.

Referring to the drawing, there is shown therein a box open at the top with a back A, ends B, B and a front C. The box is formed of a single piece of pasteboard stamped to the proper shape, the ends B, B being bent up from the back A, and the lower edge of A being bent forward to form the bottom, and then upward to form the front C. The ends will be secured at their forward edges to the front C in any suitable way, and the whole covered with ornamental paper. Inside the box is a rack built up of pasteboard strips in a peculiar way to provide the required support for the bottles.

At 8 is shown a bridge piece formed as a horizontal strip with notches in its edge at regular intervals and its ends turned down to rest on the floor of the box. Its horizontal central part is bent in an arched form to afford a base on which the separate bottles rest. A set of superposed pasteboard strips 2, 3 and 4 lie on the floor of the box with their ends bent up to form regularly spaced supports for the bridge 8 and also to form cells or sockets above the bridge for receiving the respective articles to be displayed. Where these three strips intersect the bridge 8 they are notched and also set into corresponding notches in the bridge, being of equal width corresponding to the space between the front and back walls of the box. Similar strips 5 and 6 are arranged between the upturned ends of 2, 3 and 4, but do not extend down to the bottom of the box. Finally a vertical key-strip 7 is applied; its lower end resting for support on the three strips 2, 3 and 4 and notched over the horizontal portions of strips 5 and 6, also over the bridge 8. It will be manifest that all of these strips are simple stampings and the assembling of them to form the aforesaid rack is an inexpensive matter. The bottles or other articles may be brought close together and will follow an arched course corresponding to the arched outline of the walls A and C and, moreover, will be securely upheld. The removal of a part of the bottles will not cause those remaining to fall over sideways, each one having its independent support in its own receiving cell or socket.

What we claim as new and desire to secure by Letters Patent is:

1. A display box of the character described open at its top and provided with a series of individual receiving cells formed by a bridge piece having bent ends resting on the bottom of said box, and partition strips resting on the bottom of the box and engaging said bridge piece.

2. A display box of the character described open at its top and provided with a series of individual receiving cells formed by a bridge piece, a key strip supported at its lower end within said box and engaging said bridge piece, and partition strips also supported at their lower ends within said box and engaging said bridge piece.

3. A display box of the character described open at its top and provided with a series

of individual receiving cells formed by a bridge piece, partition strips resting on the bottom of said box and engaging said bridge piece, a key strip supported at its lower end 5 within said box and engaging said bridge piece, and additional partition strips supported by the key strips and engaging said bridge piece.

4. A display box of the character described 10 open at its top and provided with a series of individual receiving cells formed by a bridge piece having bent ends resting on the bottom of said box, a key strip supported at its lower end within said box and engaging 15 the bridge piece, and partition strips also supported from the bottom of said box and engaging said bridge piece.

5. A display box of the character described 20 open at its top and having its front wall of reduced height and curved at its upper edge and provided with a series of individual receiving cells formed by a bridge piece arched to conform to the curvature of the front wall 25 of the box and having bent ends resting on the bottom of said box, and partition strips supported from the bottom of the box and engaging said bridge piece.

6. A display-box for bottles or other articles open at its top and provided with a 30 series of individual receiving cells formed by an arched bridge and a series of vertical partition walls of different heights intersecting and extending above the bridge.

7. A display-box for bottles or other articles open at its top and provided with a 35 series of individual receiving cells formed by strips each having a horizontal base portion and a vertical portion and transverse cell bottoms below the top of said vertical portion and above said horizontal portion.

8. A display-box for bottles or other articles open at its top and provided with in-

dividual receiving cells formed by strips having a horizontal and a vertical portion and a bridge supported by said strips at a point 45 below the tops of the strips and above their horizontal portion.

9. A display-box for bottles or other articles open at the top and provided with individual receiving cells formed by superposed strips turned up at spaced intervals 50 to form the sides of said cells and intersected by a horizontal bridge strip notched into the respective upturned portions of said superposed strips.

10. A display-box for bottles or other articles open at its top and provided with individual receiving cells formed by superposed strips turned up at their ends to form the sides of said cells and an arched bridge 60 strip notched into the upturned portions of said superposed strips at different distances above the floor of the box, to form the cell bottoms.

11. A display-box for bottles and other articles open at its top and provided with a series of individual receiving cells formed by two sets of superposed strips turned up 65 at their ends to form the sides of the cells, one of said sets having their horizontal portions on the floor of the box, the other set having their horizontal portions supported from below at a point above the floor of the box, together with a bridge strip forming the cell bottoms and notched into the upright 70 portions of both sets of strips aforesaid at a point below the tops of the said upright portions thereof.

Signed at New York city, county of New York, State of New York, this 5th day of 80 August, 1921.

HARVEY T. WHITE.
PERCY H. WHITE.

Certificate of Correction.

It is hereby certified that the name of the assignee in Letters Patent No. 1,442,547, granted January 16, 1923, upon the application of Harvey T. White and Percy H. White, of Brooklyn, New York, for an improvement in "Display Boxes," was erroneously written and printed as "H. Tyson White's Sons, of New York, N. Y., a partnership," whereas said name should have been written and printed as *H. Tyson White's Sons, of New York, N. Y., a partnership*, as shown by the record of assignments in this office; and that the said Letters Patent should be read with this correction therein that the same may conform to the record of the case in the Patent Office.

Signed and sealed this 17th day of April, A. D., 1923.

[SEAL.]

KARL FENNING,
Acting Commissioner of Patents.
